CLAIM

The ornamental design for a remote control, as shown and described.

DESCRIPTION

FIG. 1 is a front perspective view of a remote control showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The dot-dash broken line in FIGS. 1-2 and 4-5 defines the claim boundary and forms no part of the claimed design. The equal-length broken lines in the drawings represent portions of the remote control that form no part of the claimed design.
